CAT AND BIRD GAME

James Lee, 1130 Brookdale Ave., Bayshore, N.Y.
Filed Dec. 14, 1962, Ser. No. 244,745
3 Claims. (Cl. 273—1)

The present invention relates to games and toys, and more particularly to such games in which embossed cartoons representing cats and birds become animated in the process of the play.

The primary object of this invention is the provision of an animated toy which may be inexpensive to manufacture, easy to operate and that may be educational.

Another object of this invention is the provision of a vertical wall to support imprints of popular play-room jingles or rhymes, such as "10 little birds sitting on a fence 1 flew away and that left 9" and another such as "10 little birds sitting on a fence 2 flew away and that left 8" etc.

A further object of this invention is the provision of a horizontally disposed base having a vertical wall or board, the base and the wall joined together to form the toy proper.

An additional object of this invention is the provision of a number of embossed bird cartoons (in this case ten) which may be hingeably mounted upon the wall and means for operating the birds and in such a manner as to permit the latter to hinge away and to disappear from view when a cord or a flexible string is being pulled by the players.

This invention consists of certain other features in construction and operation and in the combination and arrangement of several parts, to be hereinafter fully described, illustrated in the accompanying drawing and specifically pointed out in the appended claims.

In describing the invention in detail, references will be had to the accompanying drawing where like character numerals denote like or corresponding parts throughout the several views, and in which:

FIG. 1 is a perspective view of a game comprising the present invention;

FIG. 2 is a fragmentary side view of FIG. 1; and

FIG. 3 is a fragmentary rear view of FIG. 1 shown in elevation.

Referring now more in detail to the drawing, a game toy 10 made in accordance with the present invention is shown in FIG. 1, including, in combination, a horizontally disposed base 11, a vertical wall or fence 12, and a longitudinally disposed element 13. It may be seen that the base 11 has a vertical flange 14 which may be provided with several holes (ten in this case), arranged equal-spaced from each other.

The vertical board or fence 12 may be provided with an imprinted or embossed legend 12a representing a play-room jingle, substantially as shown. A row of ten bird cartoons 16 (to correspond with the ten holes 15 in the flange 14) may be hingeably secured at the upper edge 17 of the board 12, by means of the flat, flexible movable, spring members 18; one end 18a of each spring member 18 is made fast to the lower section 16a of each bird in the row, while the other end 18b of the spring is held to the upper edge 17 of the wall 12 (as substantially indicated in FIG. 2).

It may be seen in FIG. 2 that an eyelet or a small ring-hook 19 is secured to the rear portion of each of the cartooned birds 16, at a small distance above the spot where the end 18a of the flat spring 18 is mounted. One end 20a of the string or cord 20 is secured to the eyelet 19, while the opposite end 20b after being passed through the hole 15a (located in the rear section of the wall 12) and the front hole 15 (in the flange 14)

2

is secured to one of the cartooned cats 22 (see FIGS. 1 and 3).

The longitudinally disposed element 13 may be shaped in the form of a tree trunk, while the vertical wall 12 may be formed to represent a fence in a garden. Each of the cartooned cats (ten in number) has its claws 23 so shaped as to catch over the top of the tree trunk 13 when the cat 22 is manually moved from its present position (near the flange 14) towards the tree trunk or log 13, in the process of the play.

To facilitate the holding of the wall 12 in an upright position, there are several stiffeners 1b provided in the rear section of the wall 12 (see FIG. 3).

It will now be recognized that in actual practice, during the playing of the game (one or more children can play together) a cartooned cat (only one cartooned cat, No. 4 is showing in the drawing for clarity, actually there are ten such cartoons) is moved manually from its original resting position near the flange 14 towards the log 13. Thereupon the claws 23 of the cat 22 are hooked over the log to hold the cartooned cat to the former. In the process of moving the cartooned cat 22 towards the log 13, the spring 18, by means of the cord 20 is pulled to operate the first cartooned bird perched upon the wall or fence. The action of the cord 20 being pulled will trip over the bird 16 to the position shown by dotted lines in FIG. 2.

This action in the game will correspond with the reading of the first line in the jingle which reads as follows:

30 "10 little birds sitting on a fence 1 flew away and that left 9." Subsequently the second bird in the row is tripped by the players. This latter operation will correspond with the second line in the jingle which is as follows: "10 little birds sitting on a fence 2 flew away and that left 8." This process of operating the toy 10 may be repeated again and again until the last of the birds 16 in the row has been tripped. This final action will correspond with the last line in the jingle which reads as follows: "10 little birds sitting on a fence they all flew away and that left 0."

With the game being at an end, the cartooned cats may be unhooked from the log 16 holding them and thus making possible for the cartooned birds on the wall 16 to assume their original vertical position. Then the game 45 may be began all over again. It is understood that the game may be played with various modifications and combinations, and the toy does not need be always operated as above described. At the discretion of the players, this or that cartooned cat may be moved toward the log 13 in turn to operate the respective cartooned bird perched on the wall 16. The various corresponding lines of the imprinted jingle 12a are being read by the players as the game progresses.

50 A careful consideration of the foregoing description in conjunction with the invention as illustrated in the drawing will enable the reader to obtain a clear understanding and impression of the alleged features of merit and novelty sufficient to clarify the construction and operation of the invention as hereinafter claimed.

60 Minor changes in shape, size, materials and rearrangement of parts may be resorted to in actual practice so long as no departure is made from the invention as claimed.

65 What I claim as new and desire to protect by Letters Patent of the United States is:

1. A game of the class described comprising, in combination, a horizontal base of rectangular contour having a vertical flange at each of the longer sides of said rectangle, a vertical board secured to one of said flanges, the other flange having a row of holes, the holes in said row located equidistant from each other, a row of holes

in the opposite flange in alignment with the holes in the first flange, a row of cartoon characters mounted to the upper edge of said vertical board, springs upon which said characters are mounted, said springs being held upright on the upper edge of said board, a row of cartoon characters disposed along the entire length of said base, and a number of flexible cords being threaded through the holes in said flanges, one end of each cord being secured to a character perched on said board with the other end being held to a character on said base, the pulling upon said cartoon characters on said base operating the cartoon characters perched to said board to operate the game.

2. The combination according to claim 1; wherein each of the springs upon which said cartoon characters are mounted is individually secured to the upper section of said vertical board, with one end each of said springs

supporting one character and with the opposite end of each spring being held to said board, an eyelet in said cartoon characters disposed above said spring, the end of said cord being held to said eyelet, the pulling upon said cord operating said cartoon characters.

3. The combination according to claim 1; and means to render said game inoperative, said means comprising a fastening member on said base, the cartoon characters upon said base each having a claw, said claws engaging said fastening member as set forth.
